Attorney

UNITED STATES PATENT OFFICE.

HUBBARD F. HURD, OF TROY, NEW YORK, ASSIGNOR TO CLUETT, PEABODY & CO. INC.,
OF TROY, NEW YORK, A CORPORATION OF NEW YORK.

FOLD-COLLAR.

1,260,542.

Specification of Letters Patent. Patented Mar. 26, 1918.

Application filed April 30, 1917. Serial No. 165,356.

To all whom it may concern:

Be it known that I, HUBBARD F. HURD, a citizen of the United States, residing at Troy, county of Rensselaer, and State of New York, have invented certain new and useful Improvements in Fold-Collars, of which the following is a specification.

Reference may be had to the accompanying drawing, and the reference characters marked thereon, which form a part of this specification. Similar characters refer to similar parts in the several figures therein.

This invention relates to the type of fold-collar the band of which has an extended end adapted to be secured between the band and the folded-over top at the other end of the collar.

As heretofore constructed, it has been customary to thus extend one end only of the band and to provide in addition to the means for securing the band to a shirt-neckband, means for securing only said single extended end between the band and the folded-over top at the other end of the collar.

Such collars were adapted for convenient use by right-handed persons only, and left-handed persons found it somewhat inconvenient and awkward to secure such extended end of the band.

If such collars were made reversible, right-handed persons found it equally inconvenient and awkward to secure the extended end of the band when the collar was in reversed form.

The principal object of this invention is to make such a collar right-handed or left-handed at will, in either its original form or reversed form.

Other objects will appear in connection with the following description.

Figure 1 of the drawing is a front view in perspective of a fold-collar embodying my invention, the ends of the collar being slightly separated.

Fig. 2 is a view of the collar opened out flat.

Referring to the drawings wherein the invention is shown in preferred form, 1 is the band, and 2 the top, of a fold-collar, the top being adapted to be folded over upon the band in use.

The band is provided with the usual front buttonholes, 3, and back buttonhole, 4,

whereby the band can be detachably secured to a shirt-neckband not shown.

The collar is made alike at both ends, both ends of the band being similarly extended as at 5, these extended ends being alternatively adapted each to enter between the band and the top at the other end of the collar.

In addition to the buttonholes, 3 and 4, the band is provided near its upper edge with four buttonholes, 6—6 7—7, the two buttonholes, 6—6 being located in the respective extended end portions 5—5 of the band, and the other two buttonholes 7—7 being located at such distances from the respective ends of the band as to coöperate each with said buttonhole, 6, in the extended end of the band at the other end of the collar.

The ends of the collar are thus adapted to overlap one another alternatively from right to left, or from left to right as may be desired; and in either case the extended end, 5, of the band which overlaps on the front side of the other extended end, 5, of the band is inserted between the band and the folded-over top at the other end of the collar and secured by a stud or collar button, not shown, inserted through its buttonhole, 6, and the coöperative buttonhole, 7, at the other end of the collar.

While I have shown buttonholes as a preferred fastening means, I wish it understood that for certain purposes of the invention any other known fastening means may be employed in place of the buttonholes.

My invention makes it possible for the wearer of the collar to overlap the ends of the band in whichever direction he may find more convenient, permitting the collar to be used with least possible inconvenience whether in original form, or in reversed form.

What I claim as new and desire to secure by Letters Patent is:

1. A fold-collar having a band and a folded-over top, said band having both ends similarly extended and each alternatively adapted to enter between the band and the top at the other end of the collar, said band having means for detachably securing the same to a shirt-neckband, and in addition thereto other fastening means on each of said extended ends of the band, and coöper-

tive therewith, means on the body of the band beneath the folded-over top for securing said extended ends of the band alternatively each between the band and folded-over top at the other end of the collar.

2. A fold-collar having a band and a folded-over top, said band having both ends similarly extended and each alternatively adapted to enter between the band and the top at 10 the other end of the collar, said band having means for detachably securing the same to a shirt-neckband, and in addition thereto be-

ing provided with four buttonholes near the upper edge of the band, two of said buttonholes being in the respective extended end 15 portions of the band, the other two of said four buttonholes being located at such distances from the respective ends of the band as to coöperate each with said buttonhole in the extended end of the band at the other 20 end of the collar.

In testimony whereof, I have hereunto set my hand this 19th day of April, 1917.

HUBBARD F. HURD.
